CLAIM

The ornamental design for a two-piece insole as shown and described.

DESCRIPTION

FIG. 1 is a front, top perspective view of a two-piece insole showing our new design;

FIG. 2 is a top plan view of FIG. 1;

FIG. 3 is a bottom plan view of FIG. 1;

FIG. 4 is a left elevational view of FIG. 1;

FIG. 5 is a right elevational view of FIG. 1;

FIG. 6 is a front elevational view of FIG. 1; and,

FIG. 7 is a back elevational view of FIG. 1.

The broken lines illustrate portions of the two-piece insole that form no part of the claimed design.

1 Claim, 5 Drawing Sheets
